HENRY F. BICKEL, OF PLAINFIELD, NEW JERSEY, ASSIGNOR TO NEW YORK AIR BRAKE COMPANY, A CORPORATION OF NEW JERSEY.

AIR-BRAKE APPARATUS.

1,124,200.

Specification of Letters Patent.

Patented Jan. 5, 1915.

Application filed March 7, 1914. Serial No. 823,087.

To all whom it may concern:

Be it known that I, HENRY F. BICKEL, a citizen of the United States, residing in Plainfield, in the county of Union and State of New Jersey, have invented an Improvement in Air-Brake Apparatus, of which the following description, in connection with the accompanying drawings, is a specification, like letters on the drawings representing like parts.

This invention relates to an air brake apparatus and more especially to that portion of the apparatus which is commonly installed on the locomotive for controlling the operation of the brakes.

The invention consists mainly in provision for automatically controlling the pressure of the air admitted to the train pipe to effect the release of the brakes as will be hereinafter described.

In the automatic air brake apparatus now generally in use the air is admitted from the main reservoir directly to the train pipe in the operation of releasing the brakes, such admission being effected by the engineer's valve when moved to release position.

The main reservoir pressure is normally about 60% greater than normal train pipe pressure and when the system is in normal condition with the brakes not applied and the engineer's valve in running position the main reservoir communicates with the train pipe through a feed valve which operates automatically to feed air from the main reservoir to the train pipe sufficiently to maintain the normal pressure in the latter.

As is well known, the brakes are caused to be applied by reducing train pipe pressure and after application are released by increasing train pipe pressure, the discharge of air from the train pipe to reduce the pressure therein and the admission of air from the main reservoir to the train pipe to increase the pressure in the latter being effected by the proper manipulation of the engineer's valve.

When the engineer's valve is moved to release position, and connection is thus established from the main reservoir direct to the main pipe, the pressure in the train pipe at the head of the train may be increased to an amount very materially greater than normal train pipe pressure although on a long train some appreciable time elapses before the rise in train pipe

pressure takes place at the rear end of the train remote from the locomotive.

Provision is made in some of the types of triple valves now commonly used in freight car equipments whereby a large sudden increase in train pipe pressure, such as is produced at the head of the train when the engineer's valve is moved to release position, causes retardation or delay in the release operation of the brakes controlled by said triple valves, so that the brakes near the head of the train are not fully released until the rise in train pipe pressure has had time to arrive at the rear end of the train and the brakes are released more uniformly throughout the length of the train than would be the case if the brakes near the head released promptly in response to the rise in train pipe pressure.

For proper operation the abnormally high excess pressure should be maintained at the head of the train a suitable length of time, for if it is maintained for too short a time, there will be an insufficient delayed or retarded release operation in the forward portion of the train, and on the other hand if the excess pressure is maintained for too long a time the auxiliary reservoirs toward the head of the train become over-charged and will cause re-application of the brakes in the forward part of the train.

With the ordinary equipment, the excess pressure condition is controlled mainly by the engineer who determines by his skill and judgment how long the engineer's valve should remain in release position before being moved to running position, and if his action is not correct, the operation of the brakes on the train will be defective or objectionable as has just been indicated.

The apparatus forming the subject of the present invention is characterized mainly by the combination with the main reservoir, engineer's valve, and train pipe, of an automatic pressure regulator interposed in the communication from the main reservoir to the train pipe which is afforded when the engineer's valve is in release position, said regulator being normally inactive or affording the usual direct communication from the main reservoir to the train pipe, but being called into action automatically at the proper time, depending upon the length of the train, to regulate the communication from the main reservoir to the train pipe.

so that the pressure in the latter cannot remain above a predetermined amount which may be from 10 to 15% above the normal train pipe pressure. This will insure the introduction of sufficient pressure to effect the proper retardation of the release action of the brakes in the fore part of the train until the release at the rear part has been effected, without danger of objectionably 10 over-charging the auxiliary reservoirs near the fore part of the train. Furthermore, in connection with the usual gages, it will afford the engineer a definite indication of the proper time to return the engineer's valve from release to running position, so that there is no excuse for his keeping the valve in release position for too short a time, while the automatic regulator will prevent objectionable over-charging if the engineer, 15 in neglect of the indication, somewhat delays the movement of the engineer's valve from release to running position.

The accompanying drawing shows in diagrammatic form the main portion of the 20 locomotive equipment of an air brake apparatus embodying this invention, some of the working valves and instrumentalities being shown as wholly or part in section. In this equipment the engineer's valve 2 and the feed valve 3 may be of usual construction, and, except for the regulating appliance 4 and the parts associated therewith, 25 may have the usual connection with the main reservoir 5 and the train pipe 6, the latter being connected by the branch 7 with the engineer's valve.

The regulating valve 4 is interposed in the connection 8, 9 from the main reservoir to the chamber 23 in the engineer's valve above the movable valve 21 therein, so that when the regulator 4 is inactive the main reservoir pressure is maintained in the upper part of the engineer's valve as usual.

The regulator 4 comprises a valve 40 controlling the port 41 forming part of the communication from the main reservoir to the engineer's valve, the stem of said valve 40 being connected with a piston 42 acted upon at one side by pressure in the chamber 43 and at the other side by a spring 440 which acts to hold the valve 40 open when there is no pressure in the chamber 43.

The admission of pressure to the chamber 43 to operate the valve 40 is controlled by a 50 governing valve 44 acted upon at one side by the spring 45 and at the other side by the pressure at any time existing in the small reservoir or measuring chamber 46 which communicates with the pressure chamber 47 of the governing valve 44 by pipes 48, 49, the latter of which also has a restricted and controlled communication with the train pipe branch 7 through the check valve 20. Said check valve is opened by pressure from 55 the measuring chamber 46 when greater than

that in the train pipe branch 7 but is closed when the train pipe pressure is greater than that in the measuring chamber 46, although a small by-pass passage 22 affords a restricted communication which permits a 70 slow flow of air from the train pipe to the measuring chamber when the pressure in the latter is less than that in the train pipe and the check valve is seated.

The regulating spring 45 of the governing valve 44 of the automatic regulator 4 is set to withstand a pressure from the chamber 46 somewhat greater than the normal train pipe pressure (say from 10% to 15% greater) so that normally the governing valve 44 remains closed and the valve 40 of the regulator remains open, and direct communication is thus established from the main reservoir to the top chamber 23 of the engineer's valve, and pressure is admitted through the port 24 of the movable valve proper 21 into the train pipe 7, 6 when the engineer's valve is moved to release position as shown in the drawing.

The mode of operation of the appliance 90 may perhaps be best understood by taking a concrete example, in which the normal main reservoir pressure may be assumed as 110 lbs., the normal train pipe pressure as 70 lbs., and the pressure at which the governing valve 44 opens as 80 lbs., determined by the force of the spring 45 in the adjustment of the apparatus. In the normal condition, when the train is running or standing with the brakes not applied, the engineer's valve 100 will be in running position in which the communication from the chamber 23 and the main reservoir to the train pipe is cut off, but communication is established through the pipe 30, 31 and the feed valve 3 from the 105 main reservoir to the train pipe 7, 6 said feed valve operating as usual to admit air from the main reservoir to the train pipe sufficiently to maintain the normal pressure of 70 lbs. therein, and shutting off said communication to prevent the pressure from rising higher in the train pipe. The brakes are applied in the usual manner by reducing train pipe pressure, and in this operation the check valve 20 opens and permits 115 the pressure in the measuring chamber 46 to fall in unison with the train pipe pressure, and after the brakes have been applied, and at the time when they are to be released, the pressure may be for example 55 lbs., in the 120 train pipe and measuring chamber 46. When the engineer moves the engineer's valve to release position as shown the air flows direct through the now open valve 40 of the regulator and the pipes 8, 9 and engineer's valve into the train pipe 7, 6 and may charge the train pipe in the forward part of the train near the locomotive to a pressure greatly in excess of the normal train pipe pressure, say for example to 100 125 130

5 pounds or more, although some appreciable time will elapse before the pressure rises toward the rear part of the train. At the same time air will flow from the train pipe into the measuring chamber 46 through the small by-pass 22 so that the pressure in the measuring chamber which was about 55 lbs. at the moment when the air was admitted to the train pipe rises slowly, the rate of rise 10 depending among other things upon the capacity of the measuring chamber 46 and of the by-pass passage 22 which are properly proportioned to produce the desired automatic action.

15 It will thus take an appreciable determinate time for the pressure in the measuring chamber 46 to rise to the amount (80 lbs.) at which it overcomes the spring 45 and causes the valve 44 to open and thus 20 admit the pressure from the chamber 46 to the chamber 43 where it acts on the piston 42 to close the valve 40 and thus to cut off further flow of air from the main reservoir into the train pipe. The over-charging of 25 the train pipe will thus be prevented, for although the pressure at the head of the train pipe may be extremely high at the moment when the regulating valve 40 is closed the cutting off of further admission 30 of air from the main reservoir will result in the train pipe pressure being promptly reduced at the head of the train by the continuing charging of the auxiliary reservoirs throughout the length of the train. The 35 measuring chamber 46 and by pass 22 are properly proportioned thus to cause the admission direct from the main reservoir to the train pipe to cease before the auxiliary reservoirs at the head of the train have had 40 time to become objectionally over-charged, and it will be recognized that the timing of the closure of the regulating valve 40 is automatically controlled to meet the requirements, for if the train is relatively long so 45 that the direct communication from the main reservoir to the train pipe may remain open for a relatively long period of time, the excess pressure at the head of the train due to direct communication with the main 50 reservoir, will be less than if the train were shorter. Consequently, the flow of air through the by-pass 22 is slower than on a shorter train, and the time required to charge the measuring chamber 46 to the determinate pressure of say 80 lbs. is greater 55 for a longer train than for a shorter one, as is required for effective operation of the brakes. Similarly if a lighter application 60 of the brakes has been made, so that the train pipe pressure has been reduced for example, only to 60 lbs., it will require less time for the measuring chamber 46 to become charged to the pressure at which it 65 will act to cause the valve 40 of the regulating device to close and thereby prevent

further maintenance of the large excess pressure in the train pipe in the forward part of the train, than is the case when a heavier application of the brakes has been made. Thus the regulating appliance including the measuring chamber and appurtenances by which its action is governed, acts automatically to vary the time in which the direct communication from the main reservoir to the train pipe is maintained to 70 meet the requirements for proper operation on trains of various lengths and for applications of the brakes of various degrees of strength.

The engineer by observing the indication of the usual train pipe pressure gage 50 will be informed as to the proper time for moving the engineer's valve from release to running position, for the train pipe pressure will at first show abnormally high 75 but after the automatically determined interval of time at the end of which the regulating device has been operated, the pressure will drop comparatively rapidly to 80 lbs., and the engineer's valve may then 85 be moved to running position, as the train pipe will thereafter be sufficiently supplied through the feed valve passage 30, 31. If, however, the engineer should delay the movement of the engineer's valve from release to running position the regulating device 90 95 would act substantially as a reducing valve to prevent train pipe pressure from rising above 80 lbs. although it would act as a feed valve to keep or bring the pressure up to 80 lbs., if the engineer's valve were left indefinitely in release position and there was sufficient air in the main reservoir to charge the system to that pressure.

When the pressure in the train pipe and 100 measuring chamber 46 falls below the amount for which the spring 45 is set the governing valve 44 closes and the pressure in the chamber 43 falls quickly by leakage so that the force of the spring 440 and main 105 reservoir pressure on the valve 40 opens the latter, and with train pipe pressure normal or at any point below that at which the spring 45 overcomes the pressure in the chamber 47 the valve 40 will remain open 110 with the regulating appliance 4 thus inactive and the main reservoir pressure maintained in the chamber 23 of the engineer's valve the same as when no regulating appliance 115 is used.

On short trains where it is not necessary or desirable that a high excess of train pipe pressure should be obtained in the release operation, the measuring chamber 46 may be cut out of action, a stop cock 60 being 120 shown as provided for that purpose. The governing valve 44 will then respond quickly to train pipe pressure and will thus operate the regulating device 4 substantially as a 125 reducing valve to prevent the train pipe 130

pressure from rising above the pressure for which the regulator is set, thus preventing serious over-charging of the system if the engineer's valve is not properly handled.

- 5 While the action of the herein described automatic regulating apparatus is especially valuable in coöperation with car equipment having provision for retarded release of the brakes at the head of long trains, its action 10 is beneficial in connection with any usual or standard car equipment.

What I claim is:

1. The combination of the main reservoir, engineer's valve, and train pipe of an 15 automatic air brake apparatus; with a pressure regulating appliance in the communication between the main reservoir and the engineer's valve, said pressure regulating appliance comprising a governing valve controlled by pressure in a pressure chamber 20 and set to cause the regulating appliance to afford free communication from the main reservoir to the engineer's valve at all pressures up to a predetermined amount in excess 25 of normal train pipe pressure but to close said communication at said predetermined point in excess of normal train pipe pressure; and a restricted communication between the train pipe and said pressure 30 chamber whereby the pressure in the latter rises more slowly than that in the train pipe when being charged directly from the main reservoir, substantially as and for the purpose described.
- 35 2. The combination of the main reservoir, engineer's valve, and train pipe of an automatic air brake apparatus; with a pressure regulating appliance in the communication between the main reservoir and the engineer's valve; a measuring chamber in communication with the train pipe and a check valve in the communication between said measuring chamber and the train pipe, said check valve being open when the pressure 40 in the measuring chamber exceeds that in

the train pipe, and there being a relatively small communication between said measuring chamber and the train pipe when said check valve is closed, the pressure in said measuring chamber governing the action of 50 the pressure regulating appliance between the main reservoir and the engineer's valve substantially as and for the purpose described.

3. The combination of the main reservoir, 55 engineer's valve, and train pipe of an automatic air brake apparatus; with a pressure regulating appliance in the communication between the main reservoir and the engineer's valve, said pressure regulating appliance comprising a governing valve controlled by pressure in a pressure chamber and set to cause the regulating appliance to afford free communication from the main reservoir to the engineer's valve at all pressures 60 up to a predetermined amount in excess of normal train pipe pressure but to close said communication at said predetermined point in excess of normal train pipe pressure; and a measuring chamber in free 65 communication with said pressure chamber of the regulating device, and a restricted communication between the train pipe and said measuring and pressure chambers whereby the pressure in the latter rises substantially later than the pressure in the train pipe when being charged directly from the main reservoir thus permitting train pipe 70 pressure to rise indefinitely for an interval of time, at the end of which the train pipe pressure is limited to the predetermined amount in excess of normal determined by the regulating appliance.

In testimony whereof, I have signed my name to this specification in the presence of 85 two subscribing witnesses.

HENRY F. BICKEL.
